SKELETON STRUCTURE

Eugene Pitou, New York, N. Y., assignor to The Patent Scaffolding Co. Inc., Long Island City, N. Y., a corporation of New York

Application June 19, 1943, Serial No. 491,456

6 Claims. (Cl. 189—1)

This invention relates to skeleton structures for building concrete huts which may be used either by the forces in the field or for storage. The invention may be also applied to the construction of shelters during air attacks.

The object of the invention is to provide a skeleton structure which may be readily shipped and readily assembled from its component parts. Such a skeleton structure when assembled may be moved in assembled condition from place to place to act as a form for repeated new applications of concrete to the exterior thereof and when the concrete is set may be readily removed therefrom to again act as a new skeleton form for further concrete shell formations.

The invention consists of a plurality of pairs of parabolic shaped metal members joined at their meeting upper ends and supported in position by transverse and longitudinal tie members, to enable the members to be supported by parallel sills which are engaged by the lower ends of such parabolic members.

The invention consists further in providing in this skeleton form structure disengagement units which upon being disengaged permit the upper assembled structure to descend and thus be removed from the concrete shell. The assembled skeleton may then be set up elsewhere to again act as a form for a new concrete hut. Or, it may be disassembled for storage, in which case the elemental parts can be readily grouped to take up very little space.

The invention will be more fully described hereinafter, embodiments thereof will be shown in the drawings, and the invention will be finally pointed out in the claims.

In the accompanying drawings,

Fig. 1 is a perspective view of the assembled skeleton form, which may be made of any longitudinal length;

Fig. 2 is a front view of Fig. 1;

Fig. 3 is a plan view of Fig. 1;

Fig. 4 is a detailed view of the disconnection means by which the assembled form may be disengaged from its supporting members or feet;

Fig. 5 is a plan view partly in section taken on line 5—5 of Fig. 4;

Fig. 6 is a perspective view of the hut which has been built around the form shown in Fig. 1 with the skeleton form itself removed therefrom and with a front closure member applied to the hut;

Fig. 7 is a horizontal section taken on line 7—7 of Fig. 6;

Fig. 8 is a detailed section taken on line 8—8 of Fig. 3; and

Fig. 9 is a vertical longitudinal section of another form of hut substantially like that shown in Fig. 6 but in which the uppermost part is provided with a conduit embedded in the concrete to act as a reinforcing member and also as a protector for electric conductors for illumination purposes.

Similar characters of reference indicate corresponding parts throughout the various views.

Referring to the drawings and more particularly to Figs. 1 and 2, one of the prime objects of the improvement is to assemble a skeleton form 10 from small components each of which takes up a minimum of shipping or trucking space, and each of which may be made by mass production. The various components may be readily shipped in their separate state to the place where they 15 are to be assembled, with the further object that the assemblage may be readily made without the use of any special tools or special knowledge or skill.

After the assemblage has been completed the 20 exterior of the structure as shown in Figs. 1 and 3 may be covered with either a metal sheathing or with reinforced tar paper covering, or the like, or with canvas, or in other cases by some suitable material which does not permit any sagging between the ribs of the completed form. The 25 use of tar paper and certain flexible meshes can be applied to form curved portions between the ribs after which concrete is applied so that a section as taken on line 7—7 of Fig. 6 and as 30 shown in Fig. 7 provides a hut, the walls of which resemble corrugations. While these corrugations add strength to the hut, in such a case where it is desirable to have both the inner and outer walls, or one of them, uncorrugated or provided with a flat surface, this may be done 35 as shown in Figure 9. Also a pipe or conduit may be placed at the uppermost part and become embedded in the concrete to act as a reinforcing member, which pipe at the top portion will provide a longitudinally straight portion when the concrete is applied and sets. An outlet 50 such as shown in Fig. 9 enables the electric conductors to be attached to a bulb socket.

After such sheathing has been applied to the exterior of the members forming the skeleton form as shown in Fig. 1, concrete is applied and allowed to set. Depending upon the use desired to be made of such a concrete shell, the depth of the concrete is determined. For localities requiring little wind resistance, or heat impedance,

or cold protection, a thinner concrete shell can be utilized. Where it is desired to provide some protection against an air attack the concrete wall is made thicker, and this may also be reinforced by a series of intervening sheet metal coverings so as to resist fragments from shells or the like.

After the concrete has been applied the hut forms a complete housing such as shown in Fig. 6, and its front or rear or both, may be provided with a louvre 10 for ventilating purposes, a door 11, window 12, etc.

In order to complete such a hut as shown in Fig. 6, the man in charge of the installation first selects the portion of the ground which may be readily flattened, then provides two shallow parallel ditches 15 cut into the ground and then fills these ditches with concrete, cement or the like. The upper surface of the configuration shown in Figs. 1 and 2 has a flat surface 16 which merges into an inclined surface 17 and this merges into a shoulder 18, which in turn merges into a flat surface 19 of substantially the same horizontal level as the surface 16. The inclination of the surface 17 is an important feature here, in that it is selected with such an angle that it acts to resist any strains resulting from the weight of the form when it is completed. Preferably this angle is 45° to the horizontal and 90° to the stress line of the members. With the parallel sills completed and of such a length as may be desired, a plurality of rib members generally indicated by 25, are placed in position in planular relationship to each other. Each of these rib members may be assembled separately on the ground and then raised in position, or they may be first partially assembled directly in position and further assemblage completed while in position. Each of the rib members consists of two primary members 26 and 27, which in turn consist of a metal tube 28, the exterior of which is parabolic in shape so that two in mirror-reverse members 28 form substantially a parabola. This configuration is selected since it is resistant to the forces of any weight applied to the exterior such as a heavier concrete. Each of the rib members 26 and 27 has a straight-line tube or rod 29, one end of which is secured at the upper part of the member 28 at 30 and the other end of which has an inclined cut-off as shown in 31 in Fig. 4 and substantially in a vertical plane with a similar inclined cut-off 32 at the end of the parabolic member 28. The two free ends of the tube 28 and the tube 29 are joined together by vertically disposed tubular members 33, the free ends of which are suitably welded or otherwise secured to the members 28 and 29. These tubular members 33 are provided with holes or openings 34 for the passage of shanks of bolts. An extension foot 35 is formed at the juncture of two tubular members providing a bifurcation 36 and the ends of these two bifurcated members 37 and 38 are also cut off in an inclined manner with the exterior surfaces thereof 37a and 38a substantially parallel with the inclined surfaces 32 and 31 of the members 28 and 29. These inclined surfaces 32 and 31a and 31 and 38a, register with each other when the extension foot 35 is aligned with the tubular members 28 and 29. These inclined surfaces 32 and 31 are in a plane which is inclined to each axis of the members 28 and 29, the member 28 being the outer member of semi-parabolic shape and the member 29 being the inner member, acting as a chord to the outer member. At the upper lateral edge portion of

the member 37 there is welded a plate 39 which extends beyond the member 37 and alongside the member 28 and this plate with another plate of exactly the same conformation and secured in the same manner by welding to the other side of the tubular member 31, acts as a sheath for the entrance of the lower ends of the tubular members 28 and 29 and their securing members 33. Preferably the lower end of this plate 39 may also be welded to the other of the bifurcated members, namely 38. Both of these plates have holes or openings which are in registration with the holes or openings 34 of the members 33 when the parts are properly assembled, and bolts 40 are provided which pass through the openings of the plates and the openings of the members 33. When the nuts of these bolts 40 are properly turned so as to secure the bolts, the lower ends of the tubular members 28 and 29 are securely fastened to the foot member 35 as shown more in detail in Fig. 5.

In Fig. 4 there is shown in dotted lines the lower end of the tubular members 28 and 29 corresponding to the position of the same when the bolts have been removed and these lower ends of the tubular members 28 and 29 have been disengaged from the sheath formed by the two plates 39.

It will be noted that while reference has been made to the parallelism of the inclined end surfaces of the respective parts, that these are not truly parallel, but provide a tolerance of about 3° so as to facilitate the assemblage and disassembly of the foot member 35 to the rib members. When the rib members 26 and 27 have thus been assembled to their foot members 35 and these foot extensions properly placed upon the inclined surface 17 of the sills 15, the upper free ends of these ribs 26 and 27 are spaced from each other by a shoulder 42 of a metallic plate having extensions 43 shown in Fig. 8. The portion 42 spaces the free ends of the parabolic members 28 and the extensions 43 are secured to the free ends of the parabolic members 28 by means of fastening devices 44. These members 43 may be single members, that is, having a width substantially the diameter of the tubular members forming the parabolic members 28, or can be arranged in a plate which extends a considerable length along the top of the form. When so extended, the various other rib members 25 are spaced from the first member as shown in Fig. 1, and thereby the rib members form a skeleton frame of any length. The fastening device 44 is a clamp of known construction and by the operation of the thumb screw 44a the spacer member 42 and the extensions 43 are fastened to the ends of the rib members 25.

Preferably also the rib members 25 are joined together by transversely lined tubes or rods 47, the ends of which are secured to an intermediate member 48 connecting the two members 28 and 29 together preferably by welding the ends of the intermediate member 48 to the inner surfaces of the tubular members 28 and 29. A clamping member 49 is then used to secure the free ends of the tube or rod 47 to the intermediate member 48. Preferably also a longitudinally disposed tube or rod 50 is placed along the lowermost surface of the member 29 and held there against by a clamping member 51 secured to the member 29. A similar longitudinal member 52 held by the clamp 53 is disposed on the other side of the skeleton form. While the longitudinal members 50 and 52 are shown somewhat spaced above the

transverse members 47, these members 50 and 52 can connect the transverse members 47 if desired.

Having thus set up and assembled the various component parts as described with the foot members 35 placed in proper position on the sills, the rib members 25 are then covered, as before stated, with either canvas, tar paper, expanded metal, sheet metal, corrugated metal or the like, and thereupon the cement or concrete is applied to the exterior of this covering member and allowed to set. The weight of this concrete is such that it somewhat bends the covering member inwardly, and when the concrete sets it forms a corrugated appearance as shown in Figs. 6 and 7.

When it is desired to disassemble the skeleton form from the set concrete, it is done by disassembling all the clamps and thereby restoring the component elements to their elemental or separate state, and such would be the case if only one hut would be built. In encampments, a large number of huts of this kind are erected. It is then desirable to use the skeleton form for another hut. All that is necessary for the disengagement of a skeleton form from the concrete shell is to disengage the bolts 40 and remove them, whereupon the entire skeleton form free from the foot members 35 can drop down away from the concrete shell. To prevent any such dropping such as to injure the parts, a group of men can support the skeleton frame by gripping the transverse members 47, or a truck with a vertically movable frame can be placed below the transverse members 47 before the disengagement of the bolts 40 and then the vertically movable frame of the truck may be carefully lowered whereby the entire skeleton frame can be lowered away from the concrete shell.

In the foregoing description in connection with Figs. 1 and 2, a concrete sill has been described. In place of such a concrete sill, a metallic sill may be provided, and in such a case these metallic sills are made of pressed steel and of a configuration conforming substantially to the outer configuration of the cement sills and these plates are made of any suitable lengths. They are nestable for shipping. In Fig. 4, the concrete sill has been replaced by such a pressed steel sill in which the two outer legs 60 and 61 are pressed into the ground and the inclined surface 63 is so arranged as to provide the necessary frictional resistance to the end of the foot extension 35. It presents an angle of about 90° to the line of stress and the surface is about 45° to the horizontal. Preferably posts 64 are driven into the ground exterior to the leg member 60 and preferably tie rods 65 are secured to the legs of these metallic sill members. At the outer end, the tie rods 65 are secured by a unit 66, and at the inner end, the tie rods 65 are secured by a unit 67. The opposite sill is connected in the same way to the tie rods. Preferably the tie rods are covered by sand or dirt, before a floor is built in. While this metallic sill is shown as an alternative form for the use of the concrete sill of Fig. 1, no claim is made thereto in this application, this being reserved for a companion application.

In Fig. 6 dormer windows 70 and a ventilator 71 are shown, and may be provided, if desired.

From the foregoing, it will have been seen that the improved rib member 25 is so shaped as to present externally thereof the contour of a parabola. These rib members are spaced longitudi-

nally from each other a suitable distance and each of the rib members consists of the outer tube member of parabolic contour strengthened by a cord member which with the rib member is vertically disengageable from the foot extension members engaging the sill. Transverse and longitudinally aligned bars or tubes held to the rib members or cord members by suitable clamps serve to hold all of the spaced rib members together in one single entity capable of being raised or lowered or moved from place to place.

Applicant has pending application Serial Number 493,055, filed July 1, 1943, allowed January 6, 1944, and application Serial Number 493,056, filed July 1, 1943, allowed May 22, 1944; both issuing on the same date as this application.

I have described several forms of my invention, but obviously various changes may be made in the details disclosed without departing from the spirit of the invention as set out in the following claims.

What I claim is:

1. In a built-up re-use skeleton structure for the making of concrete huts, comprising a plurality of rib members each comprising a semi parabolic tube, a chord tube connected at its ends with the ends of the parabolic tube, said rib members being arranged in mirror reverse, longitudinally spaced apart, and horizontal longitudinally arranged tie members each connected with the central part of said chords, and holding the rib members spaced apart, and horizontal transversely arranged tie members connecting the rib members, combined with foot members at the lower ends of the rib members disengageably connecting with said rib members, to permit removal of the rib member structure in its entirety without shifting the foot members.

2. In a built-up re-use skeleton structure for the making of concrete huts, comprising a plurality of rib-members each comprising a semi parabolic tube, a chord tube connected at its ends to the ends of the parabolic tube, said rib members being arranged in mirror reverse, and longitudinally spaced apart, longitudinal tie members connected with the central part of said chords and holding the rib members spaced apart, transverse tie members connecting the rib members having a shoulder and spaced extensions and fastening means securing said transverse tie members to the ends of the rib members combined with foot members at the lower ends of the rib members disengageably connecting with said rib members, to permit removal of the rib member structure in its entirety without shifting the foot members.

3. In a skeleton frame member for constructing concrete huts, the combination of a rib member having two convergent tubes having end surfaces inclined to the axis of the tubes, and means for securing said tubes together, with a foot member having two divergent tubes with end surfaces inclined to the axis of the tubes, and having parallel plates acting as a sheath for the reception of the rib member, and means for fastening said sheath plates to the rib member, said inclined ends abutting each other and being substantially vertical.

4. In a skeleton frame member for constructing concrete huts, the combination of a rib member having two convergent tubes having end surfaces inclined to the longitudinal axis of the tubes, and cross tubes with openings securing said convergent tubes together, with a foot member having two divergent tubes with end surfaces

inclined to the longitudinal axis of the tubes, and having parallel plates with registering bolt openings forming a sheath for the reception of the rib member, and bolts passing through the openings in the plates and in the cross tubes, the inclined end surfaces abutting each other and being substantially vertically disposed, whereby upon the removal of the bolts, the rib member can drop by gravity away from the foot member.

5. As an article of manufacture, a rib member having an outer member of a semi-parabolic shape and an inner chord member having its ends connected with the outer member near its ends, one end of the outer member extending beyond the end of the chord member and both 10 of the other ends of the outer member and chord member having end surfaces disposed in the same plane, said plane being inclined to the axis of said outer member and of said chord member, and a central connecting member connecting the 15

median parts of said outer member with said chord member.

6. As an article of manufacture, a pair of rib members each composed of a semi-parabolic outer member and an inner chord member, the chord member having its ends connected with the outer member near its ends, one end of the outer member extending beyond the end of the chord member and both of the other ends of the outer member and of the chord member having ends disposed in the same plane, which plane is inclined to the axis of said outer member and of said chord member, means connecting the median parts of the outer member with the chord member, said rib members forming a pair in mirror reverse, and means detachably connecting each of said pairs of said rib members with each other at the ends of the outer members extending beyond said chord members.

EUGENE PITOU.
